[57] CLAIM

The ornamental design for a relish tray, as shown and described.

DESCRIPTION

FIG. 1 is a top plan view of a relish tray showing my new design;

FIG. 2 is a bottom plan view thereof;

FIG. 3 is a rear elevational view of FIG. 1;

FIG. 4 is a front elevational view of FIG. 1;

FIGS. 5 and 6 are, respectively, right side and left side

elevational views of FIG. 1; and

FIG. 7 is a sectional view as taken along the lines 7—7

in FIG. 1.

FIG. 1

FIG. 2
